UNITED STATES PATENT OFFICE.

DANIEL R. WELLS, OF READING, PENNSYLVANIA.

SOUND REPRODUCER FOR PHONOGRAHS AND THE LIKE.

Application filed October 2, 1925. Serial No. 60,028.

This invention relates to an amplifier for sound reproducing or regenerating machines or devices, and which is more especially intended for use on phonographs and more particularly in reproducing musical records, but the essential features of which may also be used in connection with radio sound reproducers.

It is well known that many sound boxes or horns at present in use in connection with the devices such as are above referred to give out harsh or metallic sounds, and it is also known that in the reproduction of musical records some notes are very imperfectly reproduced while, in some instances, some fine or delicate notes are hardly reproduced at all. This invention has for its object to obviate the objections just referred to by furnishing a sound reproducer or amplifier which, particularly in the reproduction of musical records, will give out the sounds of the instruments or voices perfectly, just as they were originally produced, preserving the original timbre of the instruments or voices. This object is carried into effect by the use of a resonator or amplifier consisting wholly of wood, and which is preferably mounted within a wooden case or cabinet. The resonator or amplifier, in its preferred form, comprises spaced-apart and partly open walls, and the case or cabinet preferably comprises spaced-apart double walls, the outer walls being preferably of open work or skeleton form, all as will hereinafter more fully appear.

In the accompanying drawings Fig. 1 is an elevation of a case or cabinet constructed in accordance with the present invention. Fig. 2 is a plan view of the same, with the cover omitted, showing the resonator or amplifier within the case or cabinet. Fig. 3 is a detail view showing a special form of the bottom of the cross member of the resonator or amplifier. Fig. 4 is a sectional elevation on line 4—4, Fig. 2. Fig. 5 is a central longitudinal section on line 5—5, Fig. 2. Fig. 6 is a sectional elevation on line 6—6, Fig. 2. Fig. 7 is a cross section of the resonator or amplifier on line 7—7, Fig. 5. Figs. 8 and 9 are elevations of the inside walls of the case or cabinet. Figs. 10 and 11 are detail views showing the connection of the stylus holder with the resonator or amplifier.

Referring to the drawings, the case or cabinet as herein shown comprises outside

walls 12 preferably of fretwork or open-work construction, as shown in Fig. 1, and inside walls 13. The inside and outside or double walls of the case or cabinet are spaced apart from each other and are connected together at intervals by blocks 14 and the cabinet is preferably mounted on a stand 15 having suitable legs 16, the cabinet being preferably raised slightly from the stand by blocks or strips 17 of cork, felt or other non-vibratory material. The inside walls 13 of the case or cabinet are preferably provided with narrow slits 13^a to increase the resonance, these slits being disposed in different ways and any suitable number thereof being provided.

Mounted within the cabinet is the usual turn-table 18 to receive the records and which will be operated in any suitable or usual manner by a motor within the housing 19. Supported on a suitable frame 20 within the case or cabinet is the resonator or amplifier which takes the place of the usual tone arm and horn of a phonograph, this resonator or amplifier consisting of a longitudinal member 21 and a cross member 22. The side walls of the longitudinal member are spaced apart from each other, as more clearly shown in Figs. 2, 6 and 7, these spaced-apart walls being connected at intervals at the top and bottom of said member by vertical cross strips 21^a, thus affording a hollow member of partly openwork construction. The side walls of the said longitudinal member 21 are provided at the portions thereof registering with the cross member 22 with a series of holes 21^b. Also, the said side walls of the longitudinal member preferably have thinned out portions 21^c of irregular shape and at irregular intervals. The top of the cross member 22 is preferably provided with slits 22^a which are shown as being straight, but which are not necessarily so, while the bottom 22^b of said cross member is provided with a series of slits 22^c which are preferably shaped and positioned to indicate the outline of the larger part of a violin. These slits increase the resonance of the thin wooden parts. The top and bottom walls of the cross member 22 of the resonator or amplifier are preferably of varying thickness, tapering as shown in Fig. 7.

The top and bottom walls of the cross member are spaced apart and connected together at their outer sides by strips or pieces

22⁴, and these top and bottom walls being also connected at the inner parts of said members by small bars or props 22⁶.

The stylus bar 23 is connected with a cross piece 24 preferably glued to disks 25 of cork, felt or linen set within thinned-out portions of the side walls of the longitudinal member 21 of the resonator or amplifier, said stylus bar being preferably mounted between 19 adjusting screws 26 tapped in lugs 27 on strips 28 at the bottom of the front portion of the longitudinal part 21 of the resonator or amplifier. This construction provided for a slight horizontal adjustment of the 15 stylus 29 carried by the holder 23, by slightly compressing either one of the small cork or felt blocks 30 interposed between the lugs 27 and the stylus holder 23.

The resonator or amplifier 21, 22 is 20 mounted on a pivot 31 so that it may accommodate itself to the record and may also be swung aside when a record is to be placed on or removed from the turn-table. The said resonator or amplifier may, if desired, 25 be properly balanced on its pivot 31 by a suitable weight, as 32, of lead or other heavy material.

It will be noted that all the parts of the 30 case or cabinet and of the resonator and amplifier are of thin wood or veneer, these parts being preferably attached together by glue, thus providing a construction which will have great resonance without emitting harsh tones, as has been demonstrated in 35 practice, and capable of reproducing musical tones running from 32 to 5,000 vibrations per second. By constructing and mounting the case or cabinet and the resonator or amplifier as shown and described the entire 40 structure as shown in Figs. 1 and 2 becomes a vibratory resonant body.

One of the side walls of the longitudinal member 21 of the resonator or amplifier is 45 preferably of hard wood, as maple or birch, and the other side wall is preferably of relatively soft wood, as red-wood or fir. In both of these walls the grain of the wood runs lengthwise of the member. The upper and lower walls of the cross member 22 50 of the resonator or amplifier are preferably of soft wood, as red-wood or fir, with the grain of the wood running crosswise of the longitudinal member 21.

The invention is not to be understood as 55 being limited to the particular constructions herein shown and described, as these may be varied widely within the province of mechanical skill without departing from the scope of the invention as defined by the 60 claims hereunto appended.

Having thus described my invention I claim and desire to secure by Letters Patent:

1. A resonator or amplifier, for phonographs or the like, formed wholly of wood 65 and comprising hollow longitudinal and

cross members each having thin walls, said longitudinal member having partly open top and bottom parts, and said cross member having partly open sides and ends.

2. A resonator or amplifier, for phonographs or the like, formed wholly of wood and comprising hollow longitudinal and cross members each having thin walls, the cross member extending out on both sides of the longitudinal member.

3. A resonator or amplifier, for phonographs or the like, formed wholly of wood and comprising hollow longitudinal and cross members each having thin walls, the cross member extending out on both sides of the longitudinal member, one of the side walls of said longitudinal member being of hard wood and the other wall being of relatively soft wood, with the grain of the wood of both walls running lengthwise of said longitudinal member.

4. A phonograph having a resonator or amplifier formed wholly of wood and comprising hollow longitudinal and cross members, each having thin walls, and a stylus bar connected with the said longitudinal member.

5. A phonograph having a resonator or amplifier formed wholly of wood and comprising hollow longitudinal and cross members each having thin walls, and a stylus bar connected with the said longitudinal member, the upper and lower walls of said cross member being provided with slits to increase the resonance.

6. A phonograph comprising a case having thin, double, wooden walls the outer of which is of openwork construction, said walls being connected together at intervals, and a resonator or amplifier mounted in said case and also having thin wooden walls and to which resonator or amplifier a stylus bar is attached.

7. A phonograph comprising a case having thin, double, wooden walls the outer of which is of openwork construction, said walls being connected together at intervals, and a resonator or amplifier mounted in said case and also having thin wooden walls and to which resonator or amplifier a stylus bar is attached, said resonator or amplifier consisting of hollow longitudinal and cross members the former carrying said stylus bar.

8. A phonograph comprising a case having thin double, wooden walls, the outer of which is of openwork construction, and a resonator or amplifier mounted within said case and having thin wooden walls; whereby a structure which is wholly vibratory is provided.

9. A phonograph comprising a case having thin, double, wooden walls, the outer of which is of openwork construction, and a resonator or amplifier mounted within said case and having thin wooden walls, said

resonator or amplifier consisting of longitudinal and cross members of openwork construction; whereby an entire vibratory structure is provided, and a stylus holder carried by said longitudinal member.

10. A phonograph comprising a case having thin, double, wooden walls, the outer of which is of openwork construction, and the inner of which is provided with slits, and a hollow resonator or amplifier mounted within said case and having thin wooden walls; whereby a structure which is wholly vibratory is provided.

11. A phonograph comprising a case having thin, double, wooden walls, the outer of which is of openwork construction, and the inner of which is provided with slits, and a hollow resonator or amplifier within said case and having thin wooden walls, said resonator or amplifier consisting of longitudinal and cross members of openwork construction; whereby an entire vibratory structure is provided, and a stylus bar carried by said longitudinal member.

In testimony whereof I affix my signature.
DANIEL R. WELLS.
